UNITED STATES PATENT OFFICE.

LEWIS A. MYERS, JR., OF NEWARK, NEW JERSEY.

GARMENT-SUPPORTER.

1,049,134.

Specification of Letters Patent. Patented Dec. 31, 1912.

Application filed March 25, 1912. Serial No. 685,955.

To all whom it may concern:

Be it known that I, LEWIS A. MYERS, Jr., a citizen of the United States, residing at Newark, in the county of Essex and State 5 of New Jersey, have invented certain new and useful Improvements in Garment-Supporters, of which the following is a full, clear, and exact description.

This invention relates to garment supporters and buckles for the same, and has for its object the provision of a fastening device or buckle, of novel construction; preferably in combination with a supporting strip or member, such as a belt, suspender, or the like.

The principal aim of the invention is to so form the fastening part or buckle of such a device that the normally exposed or outer surface of the same may be quite flat and 20 devoid of hooks or other outwardly extending parts.

A further object of the invention is to provide a novel means for clamping a strip or strap in position within the buckle or 25 fastening part, the clamping means being of exceeding simplicity, and adapted to be manipulated with the greatest facility. I have furthermore aimed to so construct the said clamping means that it shall most 30 surely grasp the fabric or material inserted therethrough, whereby to hold the same against inadvertent displacement.

These, and other, objects of my invention will be hereinafter referred to, and the novel 35 elements and combinations of elements by means of which the same may be attained will be more particularly pointed out in the claim appended hereto.

In the accompanying drawings, which 40 form a part hereof, and in which like reference characters designate like parts throughout the several views; I have exemplified two preferred forms of construction; but I am aware that various modifications and 45 changes may be made in my device within the purview of my invention, and hence desire to be limited only by the scope of the said appended claim.

Figure 1 is a perspective view of a belt 50 with my novel fastening means in place thereon. Fig. 2 is an enlarged vertical section of said fastening means and belt, the section being taken on line II-II, Fig. 1. Fig. 3 is a fragmentary detail view of the 55 said fastening means, observed from the rear; showing the manner of attaching the

extremity, for example, of a belt thereto. Fig. 4 is a front elevation of a fragment of a suspender having a buckle constructed in accordance with the principles of my invention in position thereon. Fig. 5 is a transverse section of the same, taken on line V-V, of Fig. 4; the section being drawn to an enlarged scale.

In Fig. 1 the belt, which may be of 65 leather, linen, or other suitable material, has been designated 1, and the fastening means or buckle has been broadly designated 2. In the present instance this buckle comprises an annular plate or apertured 70 disk 3, which is preferably dished slightly, as shown in Fig. 2. For convenience hereinafter in describing the mode of operation of the device, the aperture in this element has been designated 4; and it will be observed that a portion of the free end 5 of the belt is preferably exposed therethrough. The annulus 2 is preferably made somewhat 75 larger in diameter than the width of the portion of the strip which is to be engaged 80 therewith; but this is by no means objectionable as it rather tends to set off the buckle. The buckle hence overlaps the belt proper upon either side thereof and ears 6 are formed, preferably integral with the 85 annulus at these overlapping portions; said ears being bent around, as best shown in Figs. 2 and 3, so as to form rearwardly directed eyes upon either side of the belt 1. These eyes have short slits 7 in the inner 90 sides thereof, which are adapted for the reception of the reduced tongue-like extremities 8 of a normally bowed clamping spring 9. This spring is made of slightly greater 95 length than can be accommodated between the ears, so that when in use it will assume the position shown in full lines in Fig. 2, wherein it is substantially concentric with the dished annulus 3. Struck up prongs or 100 tongues 10 may be provided at spaced intervals over the surface of this bowed spring, said tongues being pointed, and the points being outwardly directed from the body of the wearer toward the dished annulus. Assuming, for example, that the belt 105 be made of leather, the inner face 11 thereof is usually unfinished and this affords an excellent medium for engagement with these teeth. While, of course, at least one set of the teeth should bend generally in the 110 direction of the extremity 5 of the belt, it is advisable to provide a double set of these

teeth—the teeth of the respective sets being oppositely directed; so not only is the belt held against slippage which might tend to loosen it around the waist of the wearer; but it is further held securely against any movement whereby it might be tightened inadvertently. To release the spring pressure-piece 9 and the teeth thereof from the leather or fabric, it is merely necessary to 10 insert the thumb or finger into the aperture 4, and press the material of the belt rearwardly at this point toward the body of the wearer. This causes the bowed spring to assume a somewhat sinusoidal form, the 15 center thereof being bowed rearwardly with respect to the element 3, while the lateral portions are still in engagement with the belt surface 11. Continued rearward movement of the central portion, however, causes 20 the lateral parts to suddenly spring backwardly, when the entire resilient strip assumes substantially the form indicated in dotted lines 12, in Fig. 2; the belt at such time being freely movable between the 25 pronged spring clamp or plate and the inner surface of the dished annulus.

The apertures or eyes in the ears 6 are of sufficient size to permit of the insertion thereinto, preferably in front of the tongues 8, of the laterally directed extremities or legs 13 of a cross bar or yoke 14. The tips of the legs or ends 13 being inwardly bent as at 15, and the corresponding portions upon the opposite sides of the ears 6 being 30 also inwardly directed as at 16, in order to hold the yoke securely in position upon the rear side of the annulus. The central or main portion of this yoke is slightly offset, as shown in Fig. 2, to permit of the 35 insertion thereunder of one end of the belt 1, this end being looped therearound, and being sewed, or otherwise secured, back upon itself as at 17, in a well-known manner.

40 The operation of this form of device is as follows: The belt is placed around the waist of the wearer and the point of the extremity 5 thereof is inserted between the clamping spring 9 and the dished plate, the 45 spring being in the position designated 12 in Fig. 2. The extremity 5 of the belt is grasped by the fingers of the wearer and the belt is drawn as snugly around the waist as desired, whereupon the finger may be 50 inserted back of the buckle and pressed against the rear wall of the clamping spring, thereby driving it into engagement with the inner face 11 of the belt. Even without the provision of the tongues or prongs 10 55 the belt will be quite firmly held; but the insertion of these prongs into the belt fabric or material effectively serves to secure it still more firmly against inadvertent displacement. To remove the belt it is merely 60 necessary to press firmly against the por-

tion of the same which is exposed through the aperture 4; after which the end 5 may be freely withdrawn from the buckle.

Where a stiff or short clamping spring is used it may, in some instances, become necessary to provide auxiliary or yielding means for permitting the movement thereof from its position of disengagement to its engaging position, and vice versa; and particularly is this the case where the buckle is made of relatively small size, as for example where it is designed for a narrow belt or for use upon a suspender strap. In Figs. 4 and 5 I have exemplified such an auxiliary means which is particularly adapted to this end, and the provision of which does not materially increase the cost of the article. In Fig. 4 the part which corresponds to the dished annulus 3 is rectangular, and has been designated 3'. This member is provided with rearwardly directed ears 6, as in the preceding case; the yoke 14 having the legs 13 thereof disposed in the apertures in the ears; the yoke legs being bent as at 15 and 16, as in the previous instance. The 70 aperture of the dished member 3' is in this case substantially oblong or rectangular; although, of course, the particular shape of this aperture is immaterial; and the webbing of, for example, a suspender, is exposed therethrough exactly as is the belt in the preceding case. One extremity of this webbing may be doubled back upon itself around the yoke, as at 18, and sewed or otherwise secured thereto in the usual manner. The clamping spring 9' is preferably provided with teeth 10 and tongues 8; the latter at the extremities thereof, so that it has much the same shape as the spring 9 previously described. The essential difference herein resides in the provision of a 75 series of flutings or corrugations 19 on this clamping piece; said corrugations extending laterally across said piece. Any suitable number of flutings or corrugations may be provided, but I find that usually one or two at each end of the normally bowed clamp are sufficient. Their function is to enable the piece to be readily snapped into and 80 out of engagement with the webbing, or other material, which the buckle is intended to engage. When, for example, the finger is pressed against the material 1', exposed through the opening 4', these laterally extending corrugations being resilient, as is 85 the rest of the strip, will in effect be crumpled up or driven together slightly so as to take up in a large measure the difference in overall length between the arc which the 90 resilient strip normally conforms to, and the 95 said arc. This feature, while small, I regard as of considerable value, in that it permits of a successful use of the buckle in connection with strips or straps of material 100 which are relatively quite narrow in width. 130

Having described my invention, I claim:—

A device of the class described comprising a dished plate having a central aperture there-
5 in and a pair of opposed eyes at the opposite edges of the plate, a spring plate extending diametrically across the back of the dished plate and having its ends engaging into the eyes, and a yoke adapted for attach-
10 ment to a strap and having its legs engag-

ing through said eyes and secured therein and against the extremities of said spring plate, whereby said eyes and yoke hold the spring plate to said dished plate.

In witness whereof, I subscribe my signa- 15
ture, in the presence of two witnesses.

LEWIS A. MYERS, JR.
